UNITED STATES PATENT OFFICE.

JOSEPH KIEREN, OF GILBERT, MINNESOTA, ASSIGNOR OF ONE-HALF TO JOHN W. MILLIGAN, OF DULUTH, MINNESOTA.

SUCTION-ROLL.

991,999.

Specification of Letters Patent.

Patented May 9, 1911.

Application filed August 19, 1910. Serial No. 577,972.

To all whom it may concern:

Be it known that I, JOSEPH KIEREN, citizen of the United States, residing at Gilbert, in the county of St. Louis and State of Minnesota, have invented certain new and useful Improvements in Suction-Rolls, of which the following is a specification.

The present invention comprehends certain new and useful improvements in suction devices of that type designed for use on paper making machines, the device being arranged particularly to remove the moisture from the paper pulp which is carried thereover by a traveling screen. It is well known that the ordinary stationary suction boxes which are commonly employed for this purpose, are quite objectionable in use. This is primarily due to the fact that there is a suction in all parts of the box at all times, the suction causing the screen to tend to cling to the box so that the movement of the screen is retarded and the friction between the parts is considerably increased. As a result, the wear on the screen is excessive and it soon becomes necessary to replace the same by a new screen, the cost of renewing the screen being quite a large item of expense.

The object of the present invention is an improved suction roller which is designed to supersede the ordinary stationary suction box and to overcome its many disadvantages, the device being rotated as the screen travels thereover in order to reduce the friction to a minimum.

A further object of the invention is a roller of this character having a plurality of separate compartments in which an induced draft is created successively in order to remove moisture from the pulp on the screen. The suction is created in only one compartment at a time and is cut off at a predetermined point so that there is no suction at the point where the screen leaves the roller, and thus the tendency to cling to the roller is prevented.

A still further object of the invention is a suction roller which is thoroughly reliable and efficient in operation, which possesses to a marked degree the characteristics of simplicity and durability and which consists of comparatively few parts and may be easily kept in repair.

With these and other objects in view that will more fully appear as the description proceeds, the invention consists in certain

constructions and arrangements of the parts that I shall hereinafter fully describe and then point out the novel features of in the appended claims.

For a full understanding of the invention and the merits thereof and also to acquire a knowledge of the details of construction, reference is to be had to the following description and accompanying drawings, in which:

Figure 1 is a front elevation, partly in central longitudinal section, of my improved suction roller; Fig. 2 is a transverse section on the line 2—2 of Fig. 1. Fig. 3 is a fragmentary perspective view of the hollow shaft; and, Fig. 4 is a view illustrating the application of the invention.

Corresponding and like parts are referred to in the following description and indicated in all the views of the drawings by the same reference characters.

A suction roller constructed in accordance with my invention includes a cylindrical drum 1 which is suitably perforated throughout its entire periphery, as indicated at 2. The drum is closed at its ends by means of heads 3 that are formed with central openings for the reception of a stationary hollow shaft or axle 4 on which the drum is rotatably mounted. The shaft extends axially through the drum and projects some distance beyond the heads 3 thereof and is mounted in proximity to its ends in suitable supports 5. A closure 6 is fitted to one end of the shaft, while the other end of the shaft is open and is adapted to be coupled to a suitable vacuum pump (not shown). A plurality of partitions 7 extend throughout the length of the drum and are disposed radially inwardly, with their inner edges preferably thickened and fitting against the shaft 4. There are preferably ten of these partitions and they divide the interior of the drum into an equal number of separate longitudinal compartments, it

being understood, however, that I do not limit myself to this particular number of partitions, but may employ any number according as found most desirable in practice. The inner edges of the partitions are spaced apart transversely so as to permit the compartments to communicate one at a time with a longitudinal row of apertures 8 which extend through the upper side of the hollow shaft within the drum. When the

drum rotates the partitions move around the shaft and the compartments are brought successively into registry with the apertures 8.

5 In order to reinforce the structure a transverse partition 9 is preferably provided within the drum at a point mid-way between the heads 3, said partition dividing each longitudinal compartment into two sections. This partition is formed with a central opening to receive the shaft 4. The heads 3 and the transverse partition 9 are formed around their central openings with laterally projecting annular flanges 10 for the purpose of providing a broad bearing upon the shaft. The flanges of the heads project inwardly within the drum, while the flange of the transverse partition extends laterally on both sides thereof.

10 Outstanding from the outer face of each head is a tubular extension 11 that is arranged concentrically with the shaft 4 and is spaced apart from the periphery thereof to provide an annular space for the reception of packing 12. A gland 13 is applied to the tubular extension to confine the packing therein and to complete the formation of a stuffing-box. The stuffing boxes provide air-tight joints between the drum and the

15 shaft.

20 Caps 14 are bolted or otherwise suitably secured to the heads 3 around the tubular extension 11, the caps extending around and substantially housing the stuffing boxes and bearing upon the shaft at points therebeyond. One of these caps is preferably formed with a cylindrical portion 15 to which a drive belt may be applied to rotate the drum on the shaft, it being understood that the rotation of the drum may be effected in any other suitable manner, if desired. Collars 16 encircle the shaft 4 between the caps 14 and the adjacent supports 5, the collars being disposed in abutting relation to the respective caps and being fixed on the shaft through the medium of set screws 17, whereby to hold the drum against the longitudinal movement on the shaft.

25 The shaft 4 is formed in its periphery with a longitudinal groove 18 which extends throughout the length of the drum and preferably terminates at points beyond the stop collars 16. The groove accommodates a pipe 19 which is designed to contain oil or other lubricant, the pipe being perforated within the drum to permit the lubricant to escape. The ends of the pipe are upturned and are connected to oil cups 20, the ends of said pipes being closed by the

30 cups so as to prevent air from being drawn through the pipe into the interior of the drum. The pipe is preferably arranged on that side of the row of apertures 8 from which the partitions 7 approach the apertures, and hence any excess lubricant fed on

the edges of the partitions will be drawn off through the apertures and will not tend to run down the partitions and drip upon the underlying portion of the screen hereinafter mentioned.

35 In practice, the suction roller is disposed transversely beneath the upper stretch of the usual endless wire screen or apron 21 the screen being suitably mounted on rollers 22. The screen is adapted to receive the wet stock, such as paper pulp, and is adapted to travel on the rollers 22 so as to carry the paper pulp across the suction roller. The screen extends around the upper portion of the periphery of the suction roller for a distance somewhat greater than the width of the uppermost longitudinal compartment. As this compartment communicates with the interior of the hollow shaft through the apertures 8, an induced draft is created so as to draw the moisture from that portion of the paper pulp opposite the uppermost compartment. The suction roller is rotated on the shaft as the screen is drawn forwardly, so as to reduce the friction between the parts to a minimum. As the suction roller turns, the said compartments thereof are moved out of registry with the apertures 8 so that the suction therein is automatically cut off before the point at which the screen leaves the suction roller is reached. This is a very important feature of the invention since it obviates the tendency of the screen to cling to the suction roller and thus reduces wear on the screen to a minimum and prevents the operation of the screen from being retarded. Upon the continued rotation of the suction roller the longitudinal compartments are successively brought into registry with the apertures 8 so that an induced draft is created therein.

40 It may be observed that it is particularly desirable to establish communication between the interior of the shaft and the drum 1 by means of the longitudinal row of apertures 8, inasmuch as the partitions 7 pass freely across the apertures in the rotation of the suction roller, the partitions having no tendency to catch or stick at this point, as would be the case if a longitudinal slot were employed in lieu of the apertures.

45 The perforations 2 of the drum are arranged in longitudinal rows and are flared or countersunk at their outer ends, as shown. The outer ends of adjacent perforations are arranged very close to each other, so as to cause the suction to be applied to the entire transverse area of the screen 21, instead of merely in spots, as would be the case if the perforations were spaced far apart.

50 Having thus described the invention, what I claim is:

1. A suction roller including a hollow shaft, a peripherally perforated drum rotatably mounted on the shaft, means for es-

tablishing communication between the interior of the shaft and the interior of the drum, stuffing boxes outstanding from the ends of the drum and fitting around the shaft to form tight joints, and caps rigidly secured to the ends of the drum around the stuffing boxes and substantially housing the stuffing boxes and bearing upon the shaft beyond the stuffing boxes.

- 10 2. A suction roller of the character described including a hollow shaft, a peripherally perforated drum rotatably mounted on the shaft, means for establishing communication between the interior of the shaft and the interior of the drum, stuffing boxes

outstanding from the ends of the drum and fitting around the shaft to form tight joints, caps secured to the ends of the drum around the stuffing boxes and substantially housing the stuffing boxes and bearing upon the shaft at points therebeyond, and collars fixed on the shaft in abutting relation to the caps to hold the drum against longitudinal movement on the shaft.

In testimony whereof, I affix my signature in presence of two witnesses.

JOSEPH KIEREN. [L. s.]
